ORE SAMPLING DEVICE

Charles H. Shaw, Tacoma, Wash., assignor to
American Smelting and Refining Company,
New York, N. Y., a corporation of New Jersey

Application August 18, 1943, Serial No. 499,087

5 Claims. (CL. 73—425)

This invention relates to apparatus for sampling material in bulk and more particularly an improved ore sampling device whereby a more accurate representative sample of the ore or concentrate is obtained.

In the sampling of bulk material such as ores, concentrates and the like as received in carload lots, it has been the practice in some instances to utilize a pipe or auger to collect increments of the material from different areas over the car which are combined to form the gross sample. Using such devices, however, it has been observed that the sample core cannot be removed completely, particularly at the bottom of the hole, because of the partial vacuum created as the sample core is withdrawn. As a result a portion of the sample is pulled away from the rest and falls back into the hole. This vacuum pulling force is accentuated when wet, sticky material is being sampled so that it is difficult to secure a truly representative sample.

It is the principal object of my invention to provide a sampling device which eliminates the formation of a partial vacuum during use of the sampler whereby a sample core of the section to be assayed can be more easily obtained.

Another object is to provide a sampling device of the character described which combines the principles of pipe and auger sampling with means for preventing a partial vacuum from forming as the sample core of material is extracted whereby the sample may be withdrawn from the pipe without loss.

Although the novel features which are believed to be characteristic of this invention will be particularly pointed out in the claims appended hereto, the invention itself, as to its objects and advantages, and manner in which it may be practiced, may be more readily understood by referring to the following description in connection with the accompanying drawing, forming a part thereof, in which

Fig. 1 is a vertical cross sectional view taken through my sampling device and illustrating the auger in position to withdraw a sample core portion, the device being shown broken away in parts to better illustrate the construction;

Fig. 2 is a plan view of the device shown in Fig. 1 with a portion of the operating handle shown broken away; and

Fig. 3 is an enlarged fragmentary view similar to Fig. 1 illustrating the position of the air vent plug when withdrawing the sample.

Referring to the drawing in detail, 10 designates a tube of suitable length which is open at

both ends and forms a casing for the sample core. The tube 10 is provided near its upper end with suitable handle means 12 which are firmly fixed thereto by means of a reinforcing band or collar 13. The collar 13 with attached handles 12 is preferably welded to the tube, as indicated in Fig. 1.

Arranged for operation in the tube 10 is an auger, generally designated 14. This auger comprises a hollow shaft 15, such as a pipe of similar length as the tube 10, which is provided at its upper end with a cross rod comprising a flattened cap portion 16 adapted to seat across the upper end of the tube 10 when the auger shaft is in its lowermost position, and crank portion 17 for turning the auger shaft during use.

On the lower end of the shaft 15 is a screw blade 18 for boring through the ore or concentrate sample core 19 as illustrated in Figs. 1 and 20. The lower extremity of the hollow shaft 15 is restricted to form a projecting vent 20 as shown on the drawing. For opening and closing this vent a rod 22 is arranged to fit loosely in the hollow auger shaft 15, its end portion being tapered to form a plug 24. The rod 22 when adjusted to its lowermost position closes the vent 20 as illustrated in Fig. 1.

During the boring operation the vent 20 is kept closed to prevent particles of the material being sampled from entering the hollow shaft 15. For manipulating the rod 22 to open or close the opening 20 a link or ring 26 is provided at its upper end which may be grasped when positioning the rod. Normally the rod 22 is held in its closed position by a spring clip 28 suitably fastened to the cap 16 which is adapted to be pivoted to one side to permit raising of the rod 22 and opening of the vent 20.

In operation of the device, for example when taking samples of ore or concentrates as received in a car where the ore covers the floor for a depth of two or three feet, a suitable template is used to lay out the places over the surface area of the car where sample cores are to be obtained. These sampling places or spots are ordinarily spaced regularly over the surface area of the car. To take the sample, the ore sampling tube 10 of my device is preferably lubricated, then grasped by the handles 12 and forced vertically down into the ore until it has penetrated approximately six inches. The auger 14 is then inserted in the tube 10 with the plug clamped in place so as to close the vent 20, as illustrated in Fig. 1. The auger shaft 15 is then rotated by means of the crank 17 to advance

the auger blade 18 through the concentrates to within approximately $\frac{1}{2}$ inch of the bottom of tube 10. When this point is reached, the plug 22 is raised so as to open the vent 20 and allow air to enter the tube below the auger blade 18. Then the auger is slowly lifted upwardly about six inches, withdrawing the six inch core up the tube. Then the tube is forced further downwardly into the bed of ore another six inches together with the auger until the latter reaches the ore then in the lower end of the tube. The vent is again closed and the auger turned until it reaches to within $\frac{1}{2}$ inch of the bottom of the tube in its new position, the vent again opened and the auger lifted, raising the core above the auger blade up the tube.

This sequence of operations is repeated in six-inch steps until the floor of the car is reached, care being taken to clamp the plug 22 in place to close the vent 20 of the auger each time before drilling successive core sections and releasing the plug before the sample core is lifted with the auger. In the last step, after drilling to the floor bottom, the auger, with a complete sample core and the tube 10 are removed as a unit from the ore which is then placed over a suitable receptacle for receiving the composite core sample.

It will be apparent from the foregoing description of my device that other means than that shown and described may be employed for admitting air below the auger blade to prevent the formation of a vacuum when withdrawing the sample core. While certain features of the invention have been particularly described and illustrated and are pointed out in the annexed claims, it will be understood that various omissions, substitutions and changes may be made by those skilled in the art without departing from the spirit and scope of the invention.

What is claimed is:

1. A sampling device of the character described comprising an elongated tubular casing which is open at both ends and adapted to be inserted in the material being sampled to confine a sample core of the material, an auger fitted in said casing and operable for boring through said sample core, means for operating said auger to bore through a portion of said sample core and for withdrawing said auger and core portion to a storage space within said casing, said auger being provided with a passage for admitting air below said auger while said sample core portion is being withdrawn to storage whereby the formation of a vacuum in the empty space created by the removal of material with said auger is prevented.

2. A sampling device of the character described comprising a tube open at both ends

which is adapted to be inserted into the material being sampled to confine a sample core of said material, auger means for boring through said sample core while retained in said tube, said auger comprising a hollow shaft for admitting air therethrough to said sample core adjacent the boring end of said auger, means for withdrawing the auger and sample core bored through while admitting air along the hollow shaft of said auger to thereby equalize the atmospheric pressure on said sample core during its withdrawal, and means for closing the hollow air passageway in said auger shaft to prevent the entrance thereto of sample core material during the boring operation.

3. A sampling device of the character described comprising a tubing having handle means fixed adjacent one end and adapted for guiding and forcing said tubing into the material to be sampled, a hollow shaft having boring means on one end arranged in said tubing for boring through the sample core confined by said tubing, a crank on the outer end of said hollow shaft for operating the boring means, said hollow shaft allowing the free passage of air from the outer end of the core to the opposite end whereby the sample core can be withdrawn without loss due to the creation of a partial vacuum in the tubing as the core sample or increments thereof are moved through the tubing.

4. In a device of the character described a tube for insertion in the material to be sampled, auger means arranged in said tube for boring through the core of material confined by said tube, said auger comprising an elongated hollow shaft through which air is vented into said tube below the lower end of the auger, a vent located at the lower end of said hollow shaft and communicating therewith which is adapted to be closed when boring with said auger, and means comprising a rod extending through said hollow shaft which is operable to maintain said vent closed during said boring and operable to open said vent when a sample core portion is being withdrawn.

5. In a sampling device of the character described the combination with an auger and tubing for obtaining sample cores of bulk material, and wherein said tubing is adapted for insertion in the material to be sampled and said auger is disposed in the tubing for boring through the core of material confined by said tubing, of means for venting the tubing below the auger when withdrawing sample core portions, said venting means being adapted to be closed during operation of said auger to bore through said sample core.
